UNITED STATES PATENT OFFICE

HARRY M. ROBERTSON, OF CLEVELAND, OHIO

KILN

Application filed May 9, 1928. Serial No. 276,306.

This invention relates to a kiln of the continuous type for heat treating or burning various kinds of ware or products. In the illustrated application of the invention I have 5 shown a kiln of this type adapted for burning ceramic products, more particularly where the same are glazed, but the invention in its broader sense may be applied to the treating of other products as well as ceramic 10 products not requiring glazing.

One object of the invention is to construct a continuous kiln in which a draft inducing means is connected therewith at or beyond the discharge end of the heating chamber, 15 whereby air and hot gases are caused to flow through the kiln in the same direction as the ware or products move.

Another object of the invention is to construct a continuous kiln in which a draft inducing means is connected therewith at or beyond the discharge end of the heating chamber and means are provided for discharging heated air into the preheating chamber, whereby the heated air, under the influence of 25 the draft inducing means, flows through the kiln in the same direction as the products or ware move.

Another object of the invention is to provide in a continuous kiln having a preheating 30 chamber, a firing or heating chamber and a cooling chamber, means at the inner end of the cooling chamber for drawing heated air therefrom, and a separate suction means inwardly of the air drawing off means to induce a draft through the preheating and 35 heating chambers in the direction in which the products move therethrough.

Another object of the invention is to provide an improved continuous kiln capable of 40 rapidly and economically glazing ceramic ware or products.

Other objects of the invention will be apparent to those skilled in the art to which my invention relates from the following description 45 taken in connection with the accompanying drawings, wherein

Fig. 1 is a horizontal section showing diagrammatically a kiln embodying my invention.

50 Figs. 2, 3, 4, 5, 6, 7 and 8 are sections en-

larged, on the lines 2—2, 3—3, 4—4, 5—5, 6—6, 7—7, and 8—8 of Fig. 1.

Fig. 9 is a fragmentary vertical section.

Fig. 10 is a section on the line 10—10 of Fig. 3.

In the drawings, 1 indicates a bed formed of suitable material, such as reinforced concrete. The bed is shown more or less diagrammatically, but it may be of any desired construction capable of supporting the kiln 55 structure.

The kiln comprises vertical side walls 2 reinforced by spaced uprights 3 secured at their lower ends in the bed 1 and tied at their upper ends by rods 4. Each wall 2 comprises 60 an inner portion 2^a formed of suitable refractory material, an outer portion 2^b and an intermediate portion 2^c formed of suitable insulating material. The inner and outer portions are constructed of slabs or bricks. 5 indicates caps or base members extending along the upper ends of the wall portions 2^a, 2^c, and supported thereby and ledges 2^b' on the inner surface of the wall portion 2^b. The caps 5 form bases or abutments for the opposite side 65 edges of the roof 6, which is preferably arch shaped. The construction of the roof 6 will be later described. 7 indicates benches extending longitudinally of the kiln and forming between them the passage or traversing 70 space for suitable trucks or carriers A (Fig. 8) which support the products or ware. The trucks or carriers may be of any desired construction and arranged to run on tracks 7' (the tracks being omitted from Fig. 1 for 75 sake of clearness). Any suitable means may be provided for moving the carriers through the kiln and returning them to the inlet end thereof.

The kiln comprises generally a preheating 80 chamber 8 in which "water smoking" of the products B takes place, a heating chamber 9 in which oxidizing and vitrifying temperatures are maintained, and a cooling chamber 10, these chambers being in contiguous relation so that the loaded trucks or carriers A 85 may pass successively through them. The receiving or outer end of the preheating chamber 8 may have an extended section 11, its open end being closed by a door (not 90

shown), and the discharge end of the cooling chamber 10 may be provided with an extended portion 12, having at its exit a suitable door (not shown). The section 12 may also be provided with a supplemental cooling means 13, such as banks of pipes through which air is circulated in any well known manner.

10 The heating of the chamber 9 is effected by combustion of fuel in a plurality of primary combustion chambers or boxes 14 formed in each wall 2. As shown in Fig. 8, each fire chamber leads inwardly from the outer side of the wall 2, its inner upper end connecting 15 with a secondary combustion chamber 15 above and extending longitudinally of the adjacent bench 7. Each secondary combustion chamber comprises a rear refractory wall 16, a front checkered wall 17 both extending upwardly approximately to the 20 height of the loads B on the carriers A, (Fig. 8) and a top 18 formed of refractory material and resting on the walls 16 and 17.

As shown in Fig. 1, I provide in each wall 25 2 three primary combustion chambers 14 (which may be termed the main primary combustion chambers); and as also shown in this view I provide a supplemental primary combustion chamber 19 between the preheat- 30 ing chamber 8 and the heating chamber 9. In this arrangement of the primary combustion chambers the heating of the products may be effectively controlled and any one or more may be shut down when desired. I 35 have shown the chambers 14 and 19 as adapted for burning coal, coke or other form of lump material, but if desired these chambers may be constructed for the combustion of powdered fuel, oil or gas.

40 20 indicates means for creating a glazing atmosphere within the traversing passage, these means being arranged at a point beyond the heating means so that glazing may be effected after the surfaces of the products B
45 are in melted condition.

15 The means 20 may be of any suitable form to effect burning of salt (sodium chloride) the effect of which is to generate and supply to the traversing passage the necessary atmosphere for glazing the surfaces of the product. The means 20 shown for illustration purposes comprises a combustion chamber 20' provided in one wall 2 or (by preference) each of said walls 2 in opposed relation. Each combustion chamber herein shown consists of a fire box and a grate for the combustion of fuel, the salt being mixed with the fuel or thrown on the fire bed in suitable quantities. As the fire boxes or 55 combustion chambers 20' are open exteriorly of the walls 2, the salt may be supplied thereto from time to time as desired.

Each combustion chamber 20' communicates with the passage for the products through an opening 20^a, the outer side wall of

which is inclined toward the traversing passage so that the glazing atmosphere may be readily collected by the induced draft (to which reference will later be made) flowing toward the discharge end of the kiln and carried along therewith to insure glazing of the products B. The products herein shown consist of piping formed from clay and are preferably set on end on the carrier and on each other.

21 indicates headers disposed opposite each other on the benches 7 at a point in the traversing passage beyond the opening 20^a. These headers are formed with chambers 22 into each of which leads a discharge port 23 extending through its inner end wall. From each of the chambers 22 leads a discharge pipe 24 connected at its outer end to an exhaust flue 25. The flues 25 are connected to the inlet port of a suction mechanism, such as a power driven fan indicated generally at 26, driven by a motor 27. The fan 27 serves to set up a draft through the kiln from its inlet end to the headers 21 and hence causes a flow of the heated air discharged into the preheating chamber and the hot gases and products of combustion from the secondary combustion chambers through this portion of the kiln, as indicated by the arrows in Fig. 1.

28 indicates lateral recesses formed in the walls 2 in opposed relation to each other. As shown, the recesses 28 are disposed between the fire box 20' or opening 20^a and the discharge headers 21. The recesses 28 serve as reservoirs into which the mixed air, gases and glazing atmosphere may expand or circulate to retard their flow and also change the direction of their flow (see arrows in Fig. 1) so as to insure a circulation thereof in, around and into the products B being treated. The outer side walls of the recesses 28, that is, the side walls toward the discharge end of the kiln, are disposed in a converging relation to guide the gaseous products into the traversing passage.

In the construction herein disclosed I provide means for heating air and conveying such air to the preheating chamber 8, into which it is discharged, preferably at spaced points throughout its length, for preheating the products before they enter the heating chamber and effect a removal of moisture therein; this heating being known as "water smoking." For this purpose each side wall 2 at the outer end of the cooling chamber is formed with an air inlet 29 which communicates with a header 30. From each header 30 a series of pipes 31 (preferably rectangular in cross section and spaced from each other) extends to a header 32 disposed at the inner end of the cooling chamber 10, but at a point beyond or outwardly of the discharge headers 21. Intermediate their connection with the headers 30 and 32, the pipes of each series are supported by spaced piers 33, the

5 pipes extending through the latter, as shown in Fig. 6. The lower ends of the headers 32 are connected with conduits 34 which in turn are connected to a main conduit 35 extending transversely of but below the bed 1. The 10 conduit 35 leads to a pipe 36, which is connected to the inlet port of a power driven fan or blower 37, which serves to set up a suction and hence draws air through the pipes 31 to the headers 32. As will be understood the 15 products B are heated in the heating chamber to relatively high temperatures according to the kind of clay used for the manufacture of the products, first to an oxidizing temperature and then to a vitrifying temperature whereby the silica in the clay on the exposed surfaces of the products is melted so that it may combine chemically with the sodium in the salt, and as the products B pass through 20 the cooling chamber 10, the heat radiating from the products is utilized to heat the air flowing through the pipes 31.

38 indicates a motor for driving the fan or blower 37. 39 indicates an outlet connected 25 to the outlet port of the fan or blower 37. The outlet 39 is connected to a chamber 40 provided on the roof of the cooling chamber 10. The outlet 39 is provided with a branch 39^a which leads to the atmosphere or is connected 30 to a chimney (not shown). The outlets 39, 39^a, are provided with dampers 41, 41^a, respectively, so that the supply of heated air to the chamber 40 may be regulated at will. The chamber 40 is formed by the arch wall 6^a 35 and side, end and top walls 6^b. The inner side wall 6^b is formed with a plurality of ports 6^b' which register with the inlet ends of a plurality of supply conduits 42 formed in and extending longitudinally of the roofs 6 for the heating chamber 9 and preheating 40 chamber 8. At its opposite end each conduit 42 is provided with a branch 42^a (see Fig. 10), connected to a header 43 mounted on the adjacent benches 7. As will be understood from 45 Fig. 1, there are a plurality of headers 43 along each bench 7, each thereof being opposite a similar header on the other bench; the outermost conduits 42 are connected to the innermost headers 43, the remaining conduits 50 being respectively connected to the headers in successive order toward the inlet end of the chamber 8. To provide for the conduits 42, each of the roofs 6 for the chambers 8 and 55 9 consists of an inner arch shaped wall 6^c on which are placed rows of blocks or brick 6^a of suitable refractory material, the spaces between the rows forming the conduits 42, and an outer arch shaped wall 44 of suitable refractory material mounted on the bricks 6^a and cooperating with the wall 6^c to complete the conduits 42. To prevent loss of 60 heat the roofs 6 may be covered with insulation material 45. Each header 43 is provided 65 with a damper or valve 46 and its inner side

wall is formed with one or more outlet ports 47 through which the air is discharged.

By incorporating the conduits 42 in the roofs 6 of the chambers 8 and 9 several advantages are attained, among which may be mentioned the avoidance of exterior piping, which if used would cause loss of heat and increase the cost of construction and operation; maintenance of the air in heated condition without increasing the cost of operation; and tendency of the heat conducted through the roof walls 6^c to raise the temperature of the air flowing through the conduits as well as to keep it circulating therethrough. 70 75

In my construction of kiln, a draft inducing means is provided at or beyond the end of the heating chamber and where means are provided for generating a glazing atmosphere, the draft inducing means is provided at a point beyond such generating means, the object being to cause a flow of all gases, including free or supplied air in the kiln, to flow in the direction in which the products B move therethrough and to draw from the kiln all of such gases before entering the cooling chamber 10, so that the products B moving through the latter chamber will be unaffected by the heat of these gases and the air flowing through the pipes 31 may be utilized to absorb heat from the products to cool 80 85 them. By causing the hot gases to flow through the kiln with the products B they are heated to the desired temperatures in an economical manner and at the same time these hot gases are prevented from entering the pre-heating chamber and heating the products before the moisture is evaporated or "water smoked" therefrom; and by heating air by the heat radiated from the products due to cooling thereof and conducting it to the pre-heating chamber, the products B are heated sufficiently therein to effect removal of their moisture content before entering the heating chamber. 90 95 100 105

As the heat required for the pre-heating 110 chamber is derived from the heated products, cost of operation is reduced. The temperature of the preheating chamber is preferably maintained at approximately 300 degrees F. As the products B move through the heating chamber 9 they are heated to that temperature which will melt the silica in the material of the surfaces of the products. The salt which is burned in the fire box 20' is reduced into its component parts (chlorine and sodium), the chlorine passing off with the hot gases and products through the headers 21 and pipes 25, whereas the sodium is vaporized and combines with the silica to form on the surfaces of products B sodium silicate, which constitutes the glaze thereon. 115 120 125

In my construction of kiln the products to be glazed are moved through the successive chambers in batches or charges mounted on carriers A, the latter being introduced suc- 130

cessively into the pre-heating chamber and removed successively from the cooling chamber, so that the process of "water smoking", oxidizing, vitrifying and glazing takes place continuously and may be carried on for an indefinite period of time. Accordingly, the capacity is increased and cost of operation and labor materially reduced.

To those skilled in the art to which my invention relates, many changes in construction and widely differing embodiments and applications of the invention will suggest themselves without departing from the spirit and scope thereof. My disclosures and the description herein are purely illustrative and are not intended to be in any sense limiting.

What I claim is:

1. In apparatus of the class described, the combination of a preheating chamber and a heating chamber, said chambers being disposed in contiguous relation to form a passage for product bearing carriers, heating means for said heating chamber, means having connection with said passage at a point beyond said heating means and serving to induce a flow of the hot gases through said passage in the direction of movement of the carriers, and a lateral chamber formed in the wall of said passage between said heating means and the connection for said flow inducing means.

2. In apparatus of the class described, the combination of a preheating chamber having supply ports and a heating chamber, said chambers being disposed in contiguous relation to form a passage for product bearing carriers, heating means for said heating chamber, means having connection with said passage at a point beyond said heating means and serving to induce a flow of the hot gases through said passage in the direction of movement of the carriers and discharging them exteriorly of said chambers, and means for supplying heated water smoking atmosphere to said supply ports.

3. In apparatus of the class described, the combination of a preheating chamber having supply ports and a heating chamber, said chambers being disposed in contiguous relation to form a passage for product bearing carriers, heating means for said heating chamber, means having connection with said passage at a point beyond said heating means and serving to induce a flow of the hot gases through said passage in the direction of movement of the carriers and discharging them exteriorly of said chambers, means for conveying air through a portion of said passage beyond said flow inducing means and conducting the heated air to said supply ports.

4. In apparatus of the class described, the combination of a preheating chamber having supply ports in spaced relation lon-

gitudinally thereof, and a heating chamber, said chambers being disposed in contiguous relation to form a passage for product bearing carriers, heating means for said heating chamber, means having connection with said passage at a point beyond said heating means and serving to induce a flow of the hot gases through said passage in the direction of movement of the carriers, and means for supplying heated water smoking atmosphere to said supply ports.

5. In apparatus of the class described, the combination of a preheating chamber having a supply port and a heating chamber, said chambers being disposed in contiguous relation to form a passage for product bearing carriers, heating means for said heating chamber, suction means connected with said passage at a point beyond said heating means and arranged to induce a flow of the hot gases through said passage in the direction of travel of the carriers and to draw hot gases and air mixed therewith from said passage, a conduit formed in the roof of said heating chamber and extending longitudinally thereof and connected with said supply port, and means for supplying air to said conduit.

6. In apparatus of the class described, the combination of a preheating chamber having supply ports disposed in spaced relation longitudinally thereof and a heating chamber, said chambers being disposed in contiguous relation to form a passage for product bearing carriers, heating means for said heating chamber, suction means connected with said passage at a point beyond said heating means and arranged to induce a flow of the hot gases through said passage in the direction of travel of the carriers and to draw hot gases and air mixed therewith from said passage, conduits formed in the roof of said heating chamber and extending longitudinally thereof and leading to one or more of said supply ports, and means for supplying air to each of said conduits.

7. In apparatus of the class described, the combination of a preheating chamber and a heating chamber, said chambers being disposed in contiguous relation to form a passage for product bearing carriers, heating means for said heating chamber, suction means having connection with said passage at a point beyond said heating means and serving to draw air and hot gases through said passage in the direction of travel of the carriers, and a lateral chamber formed in the side wall of said passage between said suction means and said heating means and arranged to retard the flow of air and hot gases through said passage.

8. In apparatus of the class described, the combination of a preheating chamber having supply ports disposed in spaced relation longitudinally thereof and a heating chamber,

5 said chambers being disposed in contiguous relation to form a passage for product bearing carriers, heating means for said heating chamber, suction means connected with said passage at a point beyond said heating means and arranged to draw hot gases and air mixed therewith from said passage, conduits formed in the roof of said heating chamber and leading to one or more of said supply ports, 10 means for supplying air to each of said conduits and a lateral chamber formed in the side wall of said passage between said suction means and said heating means and arranged to retard the flow of air and hot gases 15 through said passage.

9. In apparatus of the class described, the combination of a preheating chamber having a supply port, a heating chamber, a cooling chamber, the roofs for said preheating and 20 heating chambers being formed with a conduit connected at its outer end with said supply port, means for heating said heating chamber, and an air conduit extending longitudinally through said cooling chamber and 25 connected at its discharge end with said first mentioned conduit, said connection including means for causing a flow of the air through 30 said conduits.

10. In apparatus of the class described, the combination of a preheating chamber having a plurality of supply ports spaced longitudinally thereof, a heating chamber, a cooling chamber, the roofs for said preheating and heating chambers being formed with a series 35 of conduits each connected at its outer end to one of said ports, means for heating said heating chamber, and a conduit extending through said cooling chamber and connected with said first mentioned conduits, said connection including means for causing a flow 40 of air through said series of conduits and said air conduit.

11. In apparatus of the class described, the combination of a preheating chamber, a heating chamber, said chambers being disposed in contiguous relation to form a passage for ware bearing carriers, combustion means in communication with said passage through said heating chamber for maintaining a vitrifying temperature therein, suction means connected to the discharge end of said heating chamber for inducing a flow of air and hot gases generated by said combustion means through said chambers in the direction of 50 movement of the products, and means between said heating means and said suction means for creating a glazing atmosphere.

12. In apparatus of the class described, the combination of a preheating chamber, a heating chamber, said chambers being disposed in contiguous relation to form a passage for product bearing carriers, combustion means in communication with said passage for heating the ware as it moves through said heating chamber, means in one wall of said heat-

70 ing chamber beyond said heating means for creating a glazing atmosphere, and suction means connected to said passage beyond said glazing atmosphere creating means for inducing a flow of the hot gases through said passage of said heating chamber and of the atmosphere in said passage in the direction in which the carriers move.

13. In apparatus of the class described, the combination of a preheating chamber, a heating chamber, said chambers being disposed in contiguous relation to form a passage for product bearing carriers, combustion means in communication with the passage through said heating chamber, means in one wall of 80 said heating chamber beyond said heating means for creating a glazing atmosphere, suction means connected to said passage beyond said glazing atmosphere creating means for inducing a flow of the hot gases and atmosphere in said passage in the direction in which the carriers move, and a lateral chamber in the wall of said heating chamber disposed between said suction means and said glazing atmosphere creating means.

14. In apparatus of the class described, the combination of a preheating chamber, a heating chamber, said chambers being disposed in contiguous relation to form a passage for product bearing carriers, combustion means in communication with the passage through said heating chamber, means in one wall of 90 said heating chamber beyond said heating means for creating a glazing atmosphere, means for supplying heated air to said preheating chamber and means beyond said glazing atmosphere creating means for drawing the atmosphere from the ware passage and preventing flow thereof into passage through said heating chamber.

15. In apparatus of the class described, the combination of a preheating chamber, a heating chamber, said chambers being disposed in contiguous relation to form a passage for product bearing carriers, combustion means in communication with the passage through said heating chamber, means in one wall of 100 said heating chamber beyond said heating means for creating a glazing atmosphere, suction means connected to said passage beyond said glazing atmosphere creating means for inducing a flow of the hot gases and atmosphere in said passage in the direction in which the carriers move, and means for supplying heated air to said preheating chamber.

16. In apparatus of the class described, the combination of a preheating chamber, a heating chamber, said chambers being disposed in contiguous relation to form a passage for product bearing carriers, combustion means in communication with the passage through 110 said chamber to cause vitrification of the products, means arranged beyond said heating means for creating a glazing atmosphere 120

in said passage, separate means for maintaining a water smoking temperature in said pre-heating chamber, and means for preventing the hot gases in said heating chamber from flowing into said preheating chamber, and the glazing atmosphere from flowing into the heating chamber.

17. In apparatus of the class described, the combination of a preheating chamber, a heating chamber, said chambers being disposed in contiguous relation to form a passage for product bearing carriers, means for supplying heat into the passage through said pre-heating chamber to effect water smoking of the products while moving therethrough, combustion means in communication with the passage through said heating chamber and maintaining a temperature sufficient to mature the products as they move through the exit portion of said chamber, and means arranged beyond the heating means for creating a glazing atmosphere in said passage.

18. In apparatus of the class described, the combination of a preheating chamber, a heating chamber, said chambers being disposed in contiguous relation to form a passage for product bearing carriers, means for supplying heat into the passage through said pre-heating chamber to effect water smoking of the products while moving therethrough, combustion means in communication with the passage through said heating chamber and maintaining a temperature sufficient to mature the products as they move through the exit portion of said chamber, means arranged beyond the heating means for creating a glazing atmosphere, and means connected with said passage at a point beyond the last mentioned means for drawing from said passage the hot gases and atmosphere contained therein.

In testimony whereof, I have hereunto subscribed my name.

HARRY M. ROBERTSON.
